[57] CLAIM

The ornamental design for a lint remover, as shown and described.

DESCRIPTION

FIG. 1 is an exploded perspective view of the lint remover showing my new design.

FIG. 2 is a side elevational view thereof.

FIG. 3 is a cross-sectional view thereof taken on line 3—3 of FIG. 2 with the lint remover tape roll shown in phantom-line.

FIG. 4 is a left end view of the lint remover as shown in FIG. 2.

FIG. 5 is a right end view of the lint remover as shown in FIG. 2.

FIG. 6 is a cross-sectional view thereof taken on line 6—6 of FIG. 2.

FIG. 7 is an exploded perspective view of a lint remover showing a second embodiment of my new design.

FIG. 8 is a side elevational view of the second embodiment of my new design shown in FIG. 7 with the lint remover tape roll thereon.

FIG. 9 is a cross-sectional view of the second embodiment of my new design taken on line 9—9 of FIG. 8 and showing the lint remover tape roll in phantom-line thereon.

FIG. 10 is a left end view of the second embodiment of my new design shown in FIG. 8.
